UNITED STATES PATENT OFFICE.

JOHN WARREN VEDDER, OF WILMINGTON, DELAWARE.

DIPPER FOR DRIERS IN PAPER-MAKING MACHINES.

1,084,677.

Specification of Letters Patent.

Patented Jan. 20, 1914.

Application filed December 6, 1911. Serial No. 664,241.

To all whom it may concern:

Be it known that I, JOHN WARREN VEDDER, a citizen of the United States, residing at Wilmington, in the county of Newcastle and State of Delaware, have invented an Improved Form of Dipper for Driers in Paper-Making Machines, of which the following is a specification.

My invention relates to improvements in the construction of dippers, which are installed in revolving cylinders commonly known as driers used upon paper making machines, in what is known as the dry-part of the machine. Said dippers are also used in other machines intended for drying fabrics or granular material which pass over them, the heat being supplied internally to the cylinder by the admission of steam through an open ended journal, fitted with a so called steam-joint or stuffing box attachment, through which the steam is admitted and through which the condensation of steam in the form of water is discharged. The function of the dipper, which revolves with the drier, being to scoop or dip up the water as fast as the steam is condensed, and to elevate it so that it may be discharged through the hollow trunnion of the revolving drier cylinder. Without a dipper or some such arrangement, the condensed steam would necessarily accumulate until the drying cylinder would become half full before there would be any discharge of water.

The improvement embodied in this dipper design fits it for service in driers which are revolved at such a high rate of speed as to render previous forms of dippers unequal to the conditions to be met. So long as the water forms a collection at the bottom and is not carried around by the friction and centrifugal force of the drier, this dipper will operate. The fundamental idea being to cause the water to pass into the involute shaped funnel by reason of its relative velocity, that is, the funnel is moving upwardly while the water is running downwardly, and the result of the impact will result in passing the water into the mouth of the funnel, which immediately thereafter, revolves higher and higher so that the water runs toward the end of the dipper which is attached, or which terminates practically at the center of the drier upon which the dipper revolves. The velocity of the water is so related to the distance to be

traveled and the time which is available, as to insure that the water dipped up reaches the inner end of the dipper and is discharged into a receiver before the dipper passes the zenith and is turned downwardly.

The receiver into which the water is discharged by the dipper, is so constructed as to insure a non-return of the water, and to allow a discharge through the hollow journal of the drier, which discharge may continue practically throughout the entire revolution. This provision obviates the possibility of a reciprocating motion of the water in the dipper, and provides a practicable means for dipping periodically, and discharging, practically, constantly. A further provision is made to insure smooth action of the dipper by providing a vent to break any vacuum that might be formed in the dipper or receiver, which would retard the free discharge of the water through the drier journal.

The dipper is preferably made separate from the receiving chamber and both are preferably made of cast metal, being screwed by means of screw bolts to the inner end of the drier journal, and to the interior periphery of the drier in a secure manner to prevent its displacement.

The invention may be better understood by referring to the accompanying drawing in which—

Figure 1 is a sectional view diametrically through one end of a drying cylinder with a dipper and receiving chamber shown therein, with the dipper shown with its receiving mouth looking forward. Fig. 2 shows a cross-section of the same cylindrical drier, looking toward the end in which is fitted the dipper and its receiver. Fig. 3 is a view similar to Fig. 1, showing a trough-like dipper.

In these figures the parts bear similar letters.

The dipper "A" is shown as having a mouth with the shape of a parallelogram, one side of which closely coincides with the inner surface of the drier shell. This parallelogram is reduced in length as the dipper is extended from its outer end to its inner end, until it becomes square in form. The dipper is shaped approximately as an involute curve in a plane diametrically disposed toward the drier axis until it reaches practically its inner end, where it turns at right angles to this plane and is joined by

2
a flange bolted to the side of the receiving chamber "B." The dipper pipe "A" is provided with vent hole "F." The receiving chamber "B" is provided with an air vent at "E." The receiving chamber "B" is provided with an outlet pipe "D." It will be noted that this outlet pipe "D" is central with the axis of the drier cylinder and its journal, while the receiving chamber "B" is disposed eccentrically to this center, and the connection of the dipper "A" at the bend "C" is central to the receiving chamber "B", but eccentric to the center of the drier and discharge pipe "D." It is to be further observed that the angular location of the mouth of the dipper is 205 degrees in advance of the position of the discharge chamber.

It is evident that this general arrangement could be carried out with modifications, such as making it of sheet metal, or making it all in one piece, or by the omission of the top side of the parallelogram shaped dipper pipe, that is, by making the dipper "A" troughlike having sides and bottom only as shown in Fig. 3. These slight changes might be beneficial, depending to some extent upon the diameter of the drier and the speed of its revolutions.

30 Having described and illustrated the invention fully, I claim:—

1. In a dipper arrangement for revolving driers, a dipper practically of involute form, having its mouth secured practically in contact with the inner surface of a drying cylinder, and its discharge end secured eccentrically with the center of said drying cylinder, and a receiving chamber secured eccentrically to the drier cylinder with its discharge outlet concentric with said drier cylinder.

40 2. In a dipper arrangement for revolving driers, a dipper practically of involute form, having its mouth secured practically in contact with the inner surface of a drying cylinder, and its discharge end secured eccentrically with the center of said drying cylinder, and a receiving chamber having a vent hole and being secured eccentric to the drier cylinder with its discharge outlet concentric with said drier cylinder.

50 3. The combination of a drying cylinder, a dipper therein of involute form having its mouth in contact with the inner periphery of the cylinder, a receiving chamber within and located eccentrically to the drying chamber and having a vent and a discharge outlet, the inner end of said dipper discharging into said receiving chamber.

60 4. The combination with a revoluble cylinder or drum, of a receiving chamber within said cylinder and fixedly joined thereto and having a discharge outlet approximately concentric to the axis of rotation of the cylinder, and a curved dipper within said cylinder and fixedly joined thereto with its

receiving end near the peripheral wall of the cylinder and its other end discharging into said receiving chamber eccentrically to the axis of rotation of the cylinder.

5. The combination with a revoluble cylinder or drum, of a receiving chamber within said cylinder and fixedly joined thereto in a position eccentric to the axis of rotation of the cylinder and having a discharge outlet approximately concentric to said axis, 75 and a curved dipper within said cylinder and fixedly joined thereto with its receiving end near the peripheral wall of the cylinder and its other end discharging into said receiving chamber eccentrically to the axis of rotation 80 of the cylinder, the relative positioning being further such that when the dipper is down the receiving chamber will be up with the discharge outlet leading from what is then the bottom of said chamber and the 85 dipper communicating with what is then the upper part of said receiving chamber above the discharge outlet.

6. The combination with a revoluble cylinder or drum, of a receiving chamber within said cylinder and fixedly joined thereto in a position eccentric to the axis of rotation of the cylinder and having a discharge outlet approximately concentric to said axis, and a curved dipper within said cylinder and fixedly joined thereto with its receiving end near the peripheral wall of the cylinder and its other end discharging into said receiving chamber eccentrically to the axis of rotation of the cylinder, the receiving and discharge 90 ends of the dipper being also on approximately opposite sides of the discharge outlet of the receiving chamber, the relative positioning being further such that when the dipper is down the receiving chamber 100 will be up with the discharge outlet leading from what is then the bottom of said chamber and the dipper communicating with what is then the upper part of said receiving chamber above the discharge outlet. 105

7. The combination with a revoluble cylinder or drum, of a receiving chamber within said cylinder and fixedly joined thereto and having a discharge outlet, and a curved trough-like dipper within said cylinder and fixedly joined thereto with its receiving end near the peripheral wall of the cylinder and its other end discharging into said receiving chamber. 110

8. The combination with a revoluble cylinder or drum, of a receiving chamber within said cylinder and fixedly joined thereto and having a discharge outlet approximately concentric to the axis of rotation of the cylinder, and a curved trough-like dipper within 120 said cylinder and fixedly joined thereto with its receiving end near the peripheral wall of the cylinder and its other end discharging into said receiving chamber eccentrically to the axis of rotation of the cylinder. 125

9. The combination with a revoluble cylinder or drum, of a receiving chamber within said cylinder and fixedly joined thereto in a position eccentric to the axis of rotation 5 of the cylinder and having a discharge outlet approximately concentric to said axis, and a curved trough-like dipper within said cylinder and fixedly joined thereto with its receiving end near the peripheral wall of the cylinder and its other end discharging into 10 said receiving chamber eccentrically to the axis of rotation of the cylinder.
